DESIGN FOR A BREATHING MASK

Walter M. Boothby, and Arthur H. Bulbulian,
Rochester, Minn.

Application April 26, 1941, Serial No. 100,631

Term of patent 14 years

To all whom it may concern:

Be it known that we, Walter M. Boothby and Arthur H. Bulbulian, citizens of the United States, residing at Rochester, in the county of Olmsted and State of Minnesota, have invented a new, original, and ornamental Design for a Breathing Mask, of which the following is a specification, reference being had to the accompanying drawing, forming part thereof.

Fig. 1 is a front elevational view of a breathing mask embodying our new design.

Fig. 2 is a rear elevational view of the mask of Fig. 1.

Fig. 3 is a side elevational view of the mask of Fig. 1.

We claim:

The ornamental design for a breathing mask, substantially as shown.

WALTER M. BOOTHBY.
ARTHUR H. BULBULIAN.
